UNITED STATES PATENT OFFICE.

NICHOLAS JOSEPH MIANO, OF JAMAICA, NEW YORK, ASSIGNOR TO UNIVERSAL FIXTURE CORPORATION, OF NEW YORK, N. Y., A CORPORATION OF NEW YORK.

REVOLVING RACK.

1,294,511.

Specification of Letters Patent.

Patented Feb. 18, 1919.

Application filed December 5, 1918. Serial No. 265,398.

To all whom it may concern:

Be it known that I, NICHOLAS JOSEPH MIANO, a citizen of the United States, and resident of Jamaica, borough and county of 5 Queens, Long Island, State of New York, have invented certain new and useful Improvements in Revolving Racks, of which the following is a specification.

The main object of this invention is to 10 provide a rack designed especially to support boxes containing perforated music rolls, the rack being of such construction that the boxes will be supported in position to expose their ends in convenient position to permit 15 of an easy selection of the desired roll.

A further object of the invention is to provide a rotatable rack for supporting perforated music roll boxes in a downwardly and inwardly inclined position so that the exposed upper and outer ends of the boxes 20 will be at such an angle that the titles thereon may be readily seen and a proper selection of boxes easily made.

Another object of the invention is to provide 25 a rotatable rack for supporting perforated music roll boxes and in which the supporting surfaces will be small transverse rods so that there will be no place for the lodgment of dirt and dust.

30 In the drawing, Figure 1 is a perspective view of a rack constructed in accordance with this invention;

Fig. 2 a vertical sectional view thereof, the central supporting tube or socket being 35 broken away to more clearly show the construction; and

Fig. 3 a detail perspective view of the upper portion of one of the end posts.

Referring to the various parts by 40 numerals, 1 designates a horizontal center bar, to the ends of which are secured the central vertical end bars 2 and 3, said end bars being connected to the center bar about midway between their ends so that said bars 45 extend substantially equal distances above and below the center bar. 4 designates the end posts which are substantially equal in length to the end bars, the upper ends of all of these bars being connected together 50 by a table top 5, said top forming a convenient support for the music roll boxes when they are removed from the rack.

To the center bar is rigidly secured a depending central supporting tube 6, said tube 55 being adapted to receive a supporting swivel

post 7. The post 7 is rigidly mounted in a pedestal 8 which is adapted to rest upon the floor or other support. It is manifest that the entire rack is rotatable about the swivel post 7.

The end posts are connected to the adjacent end bars by downwardly and inwardly inclined side bars 9. The outer ends of the side bars 9 which are connected to the end post 2 are connected to the other ends of the corresponding side bars 9 of the end bar 3, by horizontal, transversely extending, front bars 10; and the inner ends of said side bars are connected together by transversely extending horizontal stop bars 11, 70 these latter bars being arranged near the central end bars 2 and 3. The front bars 10 are arranged close to the end posts 4. Each connected pair of side bars 9 is provided, near their inner ends and close to 75 the stop bars 11, with bottom bars 12, these latter bars being below the side bars 9 as shown clearly in Fig. 2. As shown in the drawing, the music roll boxes 13 rest on the bars 10 and 12, the inner ends of the boxes 80 engaging the stop bars 11. The stop bars 11 are so arranged that they prevent the inner ends of the boxes on one side of the rack contacting with the inner ends of the boxes supported on the other side of the rack. 85

A suitable stay 14 connects the lower ends of the end posts to the upper ends of the central end bars.

As shown in the drawing, the music roll boxes are supported in a downwardly and 90 inwardly inclined position so that their upper outer ends are exposed in the correct position for readily reading the title labels thereon. The boxes are also disposed in such position that they may be readily 95 grasped and withdrawn upwardly and outwardly from the rack. It is also clear that by forming all of the supporting elements of small rods there will be no place for the accumulation of dust or dirt. 100

What I claim is:

1. A rack for supporting boxes and the like comprising central vertical end bars, means for supporting said bars, end posts, downwardly and inwardly inclined side bars 105 connecting the end posts to the end bars, horizontal rods connecting the upper outer ends of the side bars, horizontal stop bars connecting the inner ends of corresponding side bars, and a bottom bar for each con- 110

nected pair of side bars, said bottom bar being below the side bars which it connects and below the coöperating stop bar whereby the boxes will be supported in a downwardly 5 and inwardly inclined position with their inner lower ends resting against the stop bars.

2. A rotatable rack comprising a center post, a swivel post therefor, vertical end 10 bars, a horizontal center bar connected to the center post and to the end bars, corner posts, downwardly and inwardly inclined side bars connecting the corner posts to the end bars, a horizontal front bar connecting 15 together corresponding side bars on opposite sides of the rack, horizontal stop bars near the inner ends of the side bars, and a bottom bar near the inner ends of the side bars, said bottom bars being out of the horizontal 20 plane of the stop bars, whereby the boxes will be supported in a downwardly and inwardly inclined position and their rear ends will engage the stop bars.

3. A rotatable rack comprising a center post, a swivel post therefor, vertical end bars, a horizontal center bar connected to the center post and to the end bars, corner posts, downwardly and inwardly inclined side bars connecting the corner posts to the end bars, a horizontal front bar connecting 25 together corresponding side bars on opposite sides of the rack, horizontal stop bars near the inner ends of the side bars, a bottom bar near the inner ends of the side bars, said bottom bars being out of the horizontal 30 plane of the stop bars, whereby the boxes will be supported in a downwardly and inwardly inclined position and their rear ends will engage the stop bars, stays connecting 35 the lower ends of the end posts with the upper ends of the end bars, and a table top rigidly connected to the upper ends of the end posts and the end bars.

In testimony whereof I hereunto affix my signature.

NICHOLAS JOSEPH MIANO.
